UNITED STATES PATENT OFFICE

2,523,130

LADY'S NECKTIE

Victor Manfred, New York, N. Y.

Application May 17, 1947, Serial No. 748,705

1 Claim. (Cl. 2—144)

1

This invention relates to an improvement in neckties for ladies, and particularly to means for providing highly reflective decorative assemblies.

Another object of the invention is to provide a necktie for ladies with design patterns or illustrative design forms and a decorative bounding ring of reflective elements grouped around the design patterns or forms to reflect light rays in all angles of projection, and to provide combined decorative designs which attract attention and lend distinction to the necktie.

Another object of the invention is the provision of a necktie for ladies with neck band straps extending from opposite sides of the tie knot and provided with cooperating male and female button snap elements for adjustably securing the neck band around the neck of the wearer.

A further object of the invention is to provide a necktie for ladies with a combination of woven designs and ornamental beads and reflective elements disposed around the designs to give decorative relief to the layout, without in any way interfering with the use of the necktie.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a plan view of the improved necktie for ladies, showing the composite design arrangement and the adjustable neck band straps.

Fig. 2 is a detail enlarged sectional view, taken on line 2—2 of Fig. 1, showing the sequence of decorative elements.

Fig. 3 is a view similar to the view of Fig. 2 of a modified form of this invention, taken on a line corresponding to the line 2—2 of Fig. 1, and showing the combination of ornamental beads and reflective cones.

Fig. 4 is an edge view of the necktie, showing the male and female coupling snap button elements.

Fig. 5 is a view similar to that of Fig. 3 of a second modified form of this invention.

Referring to the drawing, which shows the practical embodiments of the invention, 10 designates a necktie for ladies which comprises the knot or head 11, and the pendant tail or body 12, which is shown to have an approximately oval form.

The material for the knot 11 is extended to the right and left to provide neck band sections 13

and 14. A neck band strap 15 is attached to the neck band section 13 and another neck band strap 16 is attached to the neck band section 14. The neck band strap 15 is provided with a row of female button socket coupling elements 17, and the neck band strap 16 is provided with a row of male button snap stud coupling elements. These elements are spaced equally from each other, and when the two neck bands straps are placed around the neck of the user, the three male button snap studs may be coupled to the three female sockets. If the wearer has a small neck, two male studs may be coupled to two female sockets, or only one male stud may be coupled to one female socket. By the longitudinal spacing of the button snap elements, the neck band may be adjusted to fit the necks of various persons.

The face of the knot or head 11 is provided with a woven design figure 18 which may be of any design or pattern, and is provided with a bounding ring or loop 19 composed of small concave or dished metal or plastic reflective elements, and a connecting flexible cord, wire or chain 21.

The decorative reflective elements 20 are disposed so that their concave faces are exposed in front of the necktie knot or head. These elements may be formed of colored metal, plastic or glass, and appear luminous when the necktie is exposed to light rays.

30 The body or tail 12 is also provided with a series of woven design figures 22, each differing from the other to provide contrast between the different design figures. Each of these design figures is surrounded with a ring or closed loop of decorative concave elements 23, held together by a connecting cord, wire or chain 24.

35 The rings or loops of decorative reflective elements are secured to the fabric of the necktie by means of stitching which is wrapped around the wire or chain 24, in such manner that it is concealed by the decorative elements 23.

40 Some of these decorative and reflective elements may be formed convexly and arranged in alternate order between the concave reflective elements, as shown in Fig. 5. Decorative beads may also be included in the decorative loops. Referring to Fig. 5, there is shown such an arrangement which includes the concave reflectors 26, the convex reflectors 27, the beads 28, and the connecting wire, cord or chain 24.

45 The loops of decorative elements are disposed in spaced relation to the designs embraced thereby to give design contrast of a pleasing character and to lend distinction to the necktie.

50 Due to the very high reflective qualities of the

decorative loops, the necktie appears to be ornamented with loops of fire and light and has the effect of attracting attention to the wearer of the necktie.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent, is:

In a lady's necktie having a depending tail portion, a grotesquely shaped pattern woven into the tail portion, a flexible chain fixed to the front face of the tail portion, said chain being shaped to the outline of said pattern and spaced slightly from the marginal edges of said pattern, and a plurality of ornamental reflective elements se-

cured to said chain to move as the tie is worn to vary the reflective pattern.

VICTOR MANFRED.
